Fig. 5

Fig. 6

Fig. 7

FIG. 1 is a perspective view of a dictating machine containing a cassette changer showing my new design;
FIG. 2 is a left side elevational view;
FIG. 3 is a right side elevational view;
FIG. 4 is a rear elevational view;
FIG. 5 is a front elevational view;
FIG. 6 is a bottom plan view; and
FIG. 7 is a top plan view.

I claim:

The ornamental design for a dictating machine containing a cassette changer, as shown and described.
